UNITED STATES PATENT OFFICE.

ROBERT B. HAINSWORTH, OF MAYWOOD, ILLINOIS.

WHEEL PULLER.

Application filed June 26, 1922. Serial No. 570,774.

To all whom it may concern:

Be it known that I, ROBERT B. HAINSWORTH, a citizen of the United States, residing at Maywood, in the county of Cook 5 and the State of Illinois, have invented certain new and useful Improvements in Wheel Pullers, of which the following is a specification, reference being had to the accompanying drawings, forming a part thereof.

The purpose of this invention is to provide an improved tool of the type known as a "wheel puller" designed for withdrawing a wheel from a shaft or axle with which it is engaged by a taper or drive fit. It 10 consists of certain features and elements of construction in combination, as hereinafter described and shown in the drawings and as indicated by the claims.

In the drawings:

Figure 1 is a side elevation of a wheel puller embodying this invention with a considerable portion broken away to show the interior construction in section at a diametral plane.

Figure 2 is an end elevation of the device shown in Figure 1.

Figure 3 is a perspective view of the compressible clamp ring of the wheel puller.

Figure 4 is a view similar to Figure 1 showing a modified construction.

In the drawings Figure 1 shows in dotted outline a wheel hub, A, externally threaded at B and secured to a tapered shaft or axle, C, having a reduced end portion, D, which 35 extends beyond the end of the hub. This is a common form of construction for the driving wheels and axles of automobiles, and it may be understood that the threads, B, are relatively fine threads provided primarily to receive a light ornamental cap or cover to enclose the reduced end, D, of the axle, C, said reduced portion of the axle being threaded for locking the axle in place by means of a nut (not shown), bearing 40 against the end of the hub. The turning effort of the axle, C, is usually transmitted to the hub through a key, not shown. When it is desired to remove the wheel from the axle, it is necessary to exert considerable 45 pressure against the reduced end, D, and to grip the hub, A, in some manner by a device against which such pressure may react. The present invention aims to accomplish this result in a convenient and efficient manner.

The tool consists of an annular shell, 1, internally threaded at 2 for connection with

a head or central spider, 3, whose hub portion, 4, is threaded to receive the jack screw, 5, by which the pressure is to be exerted against the end portion, D, of the axle, C. 60 Within the annular shell, 1, there is carried a compressible clamping ring, 6, which is internally threaded to fit the fine threads at B, on the hub of the wheel. The outer end of the shell, 1, has an overhanging lip 65 which is inclined or beveled at 7, to engage the beveled end portion, 8, of the ring, 6; and the ring, 6, is rendered compressible by splitting it,—that is, by milling or sawing it apart at one side, thus forming a slot 70 extending transversely of the threads as indicated at 9.

At its inner end the ring, 6, is provided with lugs, 10, which engage slots or notches, 11, formed in the end of the head member, 75 3, so that when the ring, 6, is inserted in the shell, 1, with its beveled end, 8, in contact with the beveled shoulder, 7, of the shell and with the head, 3, screwed into the threads, 2, into contact with the ring, 6, the 80 said ring, 6, is locked to the part, 3, for rotation therewith. The whole assembly may then be conveniently screwed onto the threaded portion, B, of the wheel hub, the 85 threads of the ring, 6, engaging those of the hub. Then as the jack screw, 5, is screwed in against the end portion, D, of the axle, the shell, 1, will tend to be shifted axially upon the ring, 6, and by such movement the beveled shoulder, 7, crowding upon the beveled end, 8, of the ring, 6, will tend to compress the ring, forcing its threads as deeply as possible into the threaded part, B, of the hub and somewhat narrowing the slot, 9. The greater the force 90 applied by the jack screw, 5, the greater will be its compressing effect upon the ring, 6, and the more strongly will it be forced to grip the threads, B, thus insuring an effective hold upon the hub against which the jack screw may act for forcing the tapered 95 axle, C, out of the hub, A.

Preferably the end of the jack screw is squared at 12, to receive a wrench and may 100 also be provided with a transverse hole so that a rod or bar, 13, may be inserted in lieu of the wrench when convenient. As shown in Fig. 2, the slots, 11, in the head portion, 3, are formed in radial ribs or 105 spokes, 14, and the intermediate portion of the head is cored out at 15 for lightening 110 the construction.

Figure 4 shows an arrangement for utilizing the same tool on a smaller sized hub, E, having a threaded portion, F, and a tapered axle, G, with its reduced end portion shown at H. The dotted outlines include the parts, 1 and 3, and the jack screw, 5, but in place of the compressible threaded ring, 6, an adapter ring, 16, is inserted in the annular shell, 1, with the beveled lip or shoulder, 17, of the shell, 1, engaging the beveled end, 18, of the adapter ring. This ring is not threaded, but is internally smooth and fits over a threaded ring, 19, adapted to screw into the threaded part, F, of the hub, E. Said ring, 19, is provided with lugs, 20, to engage the slots, 11, of the head, 3, and at its forward end is beveled at 21, for contact with the beveled or tapered shoulder, 22, of the adapter ring, 16. The adapter ring is split at 23 and the threaded ring, 19, is split at 24, so that as the jack screw, 5, is entered against the end portion, H, of the axle, the shell, 1, is shifted slightly in axial direction upon the adapter ring, 16, and compresses it to engagement of the beveled surfaces, 17 and 18, while said adapter ring 16, transmits this compression to the inner threaded ring, 19, and further movement of the jack screw, 5, may cause some slight longitudinal shifting of the ring, 16, upon the ring, 19, whereby the beveled surfaces, 21 and 22, will act to further contract the ring, 19, and thus force its threads as deeply as possible into the threaded portion, F, of the hub, E. By virtue of the additional parts, 16 and 19, or similar adapting parts of other dimensions, the tool shown in Figure 1 may be used on a considerable range of hub sizes and its utility will be thus measurably increased.

40 I claim:

1. A wheel puller comprising a compressible internally threaded member to fit upon a threaded wheel hub; a shell enclosing said member and having a threaded head with a jack screw centered therein to engage the end of an axle in the wheel hub, said compressible member having an externally tapered part, and the shell having an internally tapered part to co-operate therewith for compressing the threaded member upon application of longitudinal pressure by the jack screw, said shell and its head being separable to permit removal of the compressible member therefrom.
- 55 2. A wheel puller comprising a compressible member internally threaded to fit upon a threaded wheel hub; a shell enclosing said member having a threaded head with a jack screw centered therein to engage the end of an axle in the wheel hub, said compressible member being a ring cut apart from end to end, externally beveled at one end to co-operate with an internally tapered part of the shell so that application of longitudinal

pressure by the jack screw may operate to 65 compress said cut ring.

3. A wheel puller comprising a compressible member internally threaded to fit upon the threaded wheel hub, a shell enclosing said member having a head with a jack 70 screw centered therein to engage the end of an axle in such hub, the compressible member having an externally tapered part and the shell having an internally tapered part to co-operate therewith, said compressible 75 member being a split ring with lugs extending from its inner end engaging notches in the head of the shell.

4. In the combination defined in claim 1, the shell and its head being screwed together 80 with the compressible member disposed between the portion of the head which is screwed to the shell and the tapered part of said shell extending opposite said head.

5. A wheel puller comprising a compressible member internally threaded to fit upon a threaded wheel hub, a shell enclosing said member having a head with a jack screw centered therein to engage the end of an axle in such wheel hub, said compressible 90 member having an externally tapered part, and the shell including a compressible adapter encompassing said compressible threaded member, said adapter having an internally tapered part to co-operate with 95 the tapered part of the compressible member and having an externally tapered portion to co-operate with an internally tapered part of the shell proper.

6. A wheel puller comprising a compressible member internally threaded to fit upon a threaded wheel hub, a shell of fixed dimensions enclosing said member with a jack screw centered therein to engage the end of an axle in such wheel hub, the compressible 105 member having an externally tapered part, and the shell including an adapter ring secured therein and formed with an internally tapered part to co-operate with the external taper of the compressible member for compressing the latter upon application of longitudinal pressure by the jack screw.

7. A wheel puller comprising a compressible internally threaded member to fit upon a threaded wheel hub, a shell encompassing 115 said member and a threaded head for the shell separably connected thereto to permit removal of the compressible member therefrom, together with a jack screw centered in the head of the shell to engage the end of an axle in the wheel hub for exerting pressure thereon, and means whereby the reaction of such pressure at the jack screw is transferred to the compressible member for increasing its grip upon the threaded hub. 120

In testimony whereof, I have hereunto set my hand this 21st day of June, 1922.

ROBERT B. HAINSWORTH.
